UNITED STATES PATENT OFFICE.

LOUISE M. SPECHT AND JOHN A. SHIMEK, OF CHICAGO, ILLINOIS.

FIREPLACE HEATER.

Application filed March 31, 1921. Serial No. 457,224.

To all whom it may concern:

Be it known that we, LOUISE M. SPECHT and JOHN A. SHIMEK, citizens of the United States, residing at Chicago, in the county of Cook and State of Illinois, have invented certain new and useful Improvements in a Fireplace Heater; and we do hereby declare the following to be a full, clear, and exact description of the invention, such as will enable others skilled in the art to which it appertains to make and use the same.

The object of the invention is to provide a heating apparatus designed for arrangement in connection with a fire place for the purpose of furnishing heat for the room or apartment in which the fire place is located and also to furnish heat through water circulation or steam to other apartments or rooms; and particularly to provide a heating apparatus of which the heating agency is electricity and of which the construction is such as to give the appearance of a coal or log fire such as ordinarily provided in open fireplace heaters, and to afford efficient means for regulating the heat to suit the requirement; and with these objects in view the invention consists in a construction, combination and relation of parts of which a preferred embodiment is shown in the accompanying drawings, it being understood that changes in form, proportion, size and details of construction and arrangement may be resorted to within the scope of the appended claims without departing from the principle involved.

In the drawings:

Figure 1 is a front view of a fireplace equipped with a heating apparatus embodying the invention.

Figure 2 is a vertical sectional view taken longitudinally through or parallel with the front of the fireplace to illustrate the arrangement of the local heating apparatus and the coils whereby heat is communicated by circulation to other apartments.

Figure 3 is an end view of the fire place.

Figure 4 is a vertical sectional view taken centrally through the same in a plane at right angles to that of Figure 2 as shown by the dotted line 4-4 of Figure 2.

Figure 5 is a horizontal sectional view of the fire place on the plane indicated by the line 5-5 of Figure 2, showing the heating unit in plan.

Figure 6 is a diagram showing the wiring system.

Figure 7 is a detail view of one of the elements of the heating unit.

Figures 8 and 9 are detail plan and edge views of the rheostat switch.

Figure 10 is a detail view of the removable end cap of the fire place whereby access to the radiator valve is afforded.

Figure 11 is a detail view of a modified form of switch.

The fire place front 20 may be of any suitable, ornamental form and structure, for example, metal, tile or the like with relatively wide hollow jambs bounding an opening 21 having a grate 22 which supports a housing 23 of cement or suitable refractory material shaped exteriorly and colored to simulate coal, logs or like fuel, within which is located a heating unit 24 and an illuminating unit 25, said housing being porous or having openings therein through which heat from the heating unit and light from the lighting unit may readily find egress, the lighting unit preferably being of an electric type and having a globe or bulb 26 under a fire like color screen 54 to give the appearance of fire and thus carry out the idea that the housing represents a bed of coals or logs similar to that used in the ordinary fire place.

In the jambs of the fire place are located the elements 27 of a radiator having an inlet provided with a controlling valve 28 accessible at one end of the fire place frame by means of a removable cap 29, shown in detail in Figure 10 and preferably held in place by means of springs 30 or the equivalent thereof, the outlet or circulating connection of the radiator being indicated at 31, and the side elements thereof being connected by the upper and lower connecting pipes 32 and 33 which respectively span the fire place above and below the opening 21 but within the zone of heat radiated from the unit 24.

The heating unit preferably consists of a plurality of elements each having a core 34 of asbestos or like material provided with a winding 35 consisting of resistance coils preferably of #21 resistance wire, coiled to an inside diameter of 1/8 of an inch and the pitch of coils to be 5/64th of an inch. This heater is in circuit with a source of electrical supply represented by the battery 36 but which obviously may be the ordinary house lighting system with which the leads or conductors 37 are connected. Said ele-

ments of the heating unit are preferably arranged in a frame as indicated in Figure 5 with side bars 38 connected by bolts 39 extending through the terminals of the cores of the elements which may as indicated in Figure 7 be provided with projections 40 or the like, for engagement with the sides of an opening 41 formed in the grate 22, and connected with each core, at opposite ends thereof are the clips 42, preferably of fibre and 43 of metal respectively, (the metal for example being copper or brass) the fibre clip is provided with brass or copper screws 44 with washers and nuts for the attachment of the conductors which connect with the extremities of the resistance coils wound upon said cores. One element of the conductor representing the circuit including the source of electrical supply is intercepted by a switch 46, shown in detail in Figures 8 and 9, said switch preferably being of the rheostat type to provide for varying the number of resistance coils included in the circuit to correspondingly vary the degree of heat to be furnished by the heating unit. In the construction of the switch shown, as above noted in Figures 8 and 9, the movable element 47 thereof is adapted to traverse contact strips 48, 49 and 50 and carries tongues 51 for respective engagement with said contact strips, said tongues and strips having yielding terminals to insure an effective closing of the circuit, and stops 52 being provided to prevent reverse or counter-clockwise movement of the arm 47 which is actuatable by a suitable button 53 located at the front of the fire place, for example beneath the fire place opening, or otherwise as may be preferred or found more convenient.

Also included in parallel with the conductors of the heating unit is connected the lighting or illuminating unit 25, above mentioned, of which the light is designed to show through the interstices in the housing to give the appearance of burning coal, a colored screen 54, for example being arranged on a suitable bracket 55 above said unit to display a colored light on the rear wall 56 of the fire place opening.

While the above indicated construction of switch is ordinarily found convenient, there may be circumstances under which a

cylindrical form of the switch may be preferred as indicated in Figure 11, wherein the contact tongues 56 are carried by a spindle 57 to which is attached the knob or button 58, said tongues being arranged in operative relation with the contact strips 59 which form respectively the terminals of the branch conductors in circuit with the resistance coils of the different elements of the heating units.

Having thus described the invention, what we claim is:—

1. A fire place heater having an electrical heating unit, a refractory housing enclosing the same, and a radiator manifold having elements arranged in the field of radiation of the unit and heated thereby. 65

2. A fire place heater having an electrical heating unit, a refractory housing enclosing the same, and a radiator manifold having elements arranged in the field of radiation of the unit and heated thereby, and connected by circulating conductors disposed respectively above and below the plane thereof. 70

3. A fire place heater having an electrical heating unit and an associated lighting unit, a refractory porous housing enclosing said units and a radiator manifold having elements arranged in the field of radiation of the heating unit and heated thereby. 75

4. A fire place heater having an electrical heating unit and an associated lighting unit, 80 a refractory porous housing enclosing said units and a radiator manifold having elements arranged in the field of radiation of the heating unit and heated thereby, the latter consisting of a plurality of elements each 85 having a refractory core provided at opposite ends with fibre and metallic clips provided with binding posts and a resistance coil winding embracing the core.

5. A fire-place heater having an electrical 90 heating unit, a housing enclosing the same, and a radiator arranged in the field of radiation of the unit and heated thereby.

In testimony whereof we affix our signatures in presence of two witnesses.

LOUISE M. SPECHT.
JOHN A. SHIMEK.

Witnesses: EDW. NUETZEL,
OTTO G. WINNEGGE.
